UNITED STATES PATENT OFFICE.

CHARLES I. WALKER, OF SAN FRANCISCO, CALIFORNIA.

ROOF STRUCTURE.

1,426,832.

Specification of Letters Patent. Patented Aug. 22, 1922.

Application filed June 1, 1920. Serial No. 385,522.

To all whom it may concern:

Be it known that I, CHARLES I. WALKER, a citizen of the United States, and a resident of the city and county of San Francisco and 5 State of California, have invented a new and useful Roof Structure, of which the following is a specification.

This invention relates to roof construction and more particularly to the construction of 10 roofs of vehicles such as railway freight cars.

It is one of the objects of the present invention to provide an extremely durable, substantial, simple and comparatively inexpensive type of roof structure and particularly 15 to provide a strong and practicable roof and ridge pole structure for freight cars.

It is another object of the present invention to secure a substantially weather-proof 20 juncture between metallic or other roof sheets and a longitudinally extending ridge pole for a freight car and also to secure a facile and practicable method for securing a running board to the ridge pole.

25 A further object of the invention is to provide a ridge pole composed essentially of a structure presenting side channels in which may be laid and secured the contiguous edges of roof sheets, and particularly to provide 30 a roof structure including an I-beam ridge pole.

The invention possesses other objects and features of advantage, some of which, with foregoing, will be made manifest in the following description of the preferred form of 35 the invention which is illustrated in the drawings accompanying and forming part of the specification. It is to be understood that it is not intended to limit the invention 40 to the embodiment shown by the said drawings and description as variations may be adopted within the scope of the invention as set forth in the claims.

Referring to the drawings:

45 Fig. 1 is a perspective of a portion of a railway freight car incorporating the present invention.

Fig. 2 is a transverse vertical sectional view showing in detail the ridge pole structure.

It is desirable to secure a simple and at the same time practicable and durable ridge pole structure and especially to secure such a structure for railway freight cars, and the 50 present invention consists of a roof struc-

ture in which there are transverse rafters or carlines upon which are laid roofing boards and upon these are laid roof sheets preferably of metal. Freight car roofs have a slight upward pitch from the eaves and 60 the present invention involves a ridge pole structure having side or lateral channels or grooves in which may be laid the upwardly turned contiguous marginal portions of the roof sheets and the invention further includes means for over-lapping the laid 65 marginal portions and for securing the same in place in the channels. Further a feature of the invention consists of the novel construction and combination of a running 70 board structure on the ridge pole.

A preferred embodiment of the invention is illustrated as comprising a car body 2 with eave joist 3 from which spring inwardly and upwardly carlines 4 which, while 75 they may be of any suitable material and form, are shown as comprising inverted channel irons. Upon the carlines are placed longitudinal roofing boards or sheathing 5 which are spaced longitudinally at the ridge 80 of the roof on each side of an interposed longitudinally extending ridge pole 6. This ridge pole may be built up or may comprise an integral continuous structure or body preferably in the form of an I-beam thus 85 providing on each side longitudinal recesses or channels.

The I-beam ridge pole 6 is securely fastened in place on the carlines 4 as by rivets, bolts or other means 7 passing through the 90 bottom flanges. Metallic roofing sheets are shown as extending in transversely laid strips 8 from the eaves of the car body upwardly to the ridge pole 6; the upper marginal portions of the roof sheets being bent 95 upwardly or flanged and snugly fitted upon the top surface of the bottom flanges and laid upright against the surfaces of the web of the I-beam 6; a marginal portion of the roof sheet being extended up well toward the bottom surface of the top flanges of the I-beam. To secure an effective weather joint and simple means for fastening the flanges or upwardly turned portions of the roofing sheet in place against the web of the 100 I-beam, longitudinally extending clamping strips 9 may be fitted into the longitudinal channels or grooves along the ridge pole and there clamped securely as by means of bolts or other devices 10 that may extend 105 110

through the fastening strips, the up-turned marginal portions of the roof sheets and through the web of the I-beam.

By utilizing sheathing 5 of a thickness substantially equal to the thickness of the bottom flanges of the I-beam or other ridge pole forming structure, it will be seen that the roofing sheet 8 will have a substantially continuous support on the sheathing and the bottom flanges 7 of the I-beam.

A further feature of the invention resides in the attachment to the top flanges of the I-beam ridge pole of a substantial running board device including a series of longitudinally extending and laterally spaced planks 11 that are bolted as at 12 or otherwise secured to transversely extending, longitudinally spaced supporting plates 13 that are riveted, bolted or otherwise attached to the top flanges of the I-beam as at 14.

From the above it will be seen that the roof structure includes a substantially continuous integral ridge pole running from end to end of the car thus providing for the desired degree of rigidity and strength of the roof and also providing a structure that is simple in its several elements and may be erected with a minimum expenditure of time and labor because of the facility with which the parts can be applied, fitted together and secured, and it will further be seen that the ridge pole structure provides for practicable and substantially weather tight joints between the roof sheets and the ridge pole proper.

A further feature of the invention resides in the eave structure which here includes a length of angle-iron 15 having one flange laid against the siding and secured by means passing through the beam or side plate 3. The top flange of the angle-iron eave molding is turned outwardly and is overlapped

by the roof sheets 8 which are turned in under the flange at 16.

45

What is claimed is:

1. A roofing structure including a ridge pole having channels in its sides, and roofing sheets having ends laid in the channels and secured therein by longitudinally extending clamping means.

50

2. A roofing structure including a ridge pole having channels in its sides, and roofing sheets having ends conforming with and lying in the channels, and clamp means for securing the sheets in said channels and to the sides of the pole.

55

3. A roofing structure including an I-beam ridge pole, sheathing extending from the bottom of the pole, roofing sheets laid on the sheathing and having their ends bent upward and laid in the channeled sides of the pole, and clamping strips extending along the channels and securing the ends of the sheets in place.

60

4. A car roof structure including an I-beam ridge pole, and roof sheets having their edges extending into the side channels of the beam, and clamping means bolted along the sheet ends.

65

5. A car roof structure including an I-beam ridge pole in the side channels of which roof sheets are laid, means for securing the laid portion of the sheets therein, the roof sheets having up-standing marginal portions, and said means including clamping strips secured along said portions, by bolts passing through the said pole.

70

In testimony whereof, I have hereunto set my hand at San Francisco, California, this 25th day of May, 1920.

CHARLES I. WALKER.

In presence of—

W. W. HEALEY,

M. E. EWING.
